REFRIGERATING APPARATUS

Jacob Smilack, Dayton, Ohio, assignor to General
Motors Corporation, Dayton, Ohio, a corpora-
tion of Delaware

Application October 31, 1934, Serial No. 750,840

9 Claims. (Cl. 62—103)

This invention relates to refrigerating apparatus and more particularly to a method of and apparatus for automatically disposing of moisture and water dripping from the cooling unit or evaporator of a refrigerating apparatus.

Mechanical refrigerators and room cooling apparatus, whether of the absorption or compression type, operating as they do to maintain a temperature in the evaporator below the temperature of the air being cooled by the evaporator act to a certain extent as driers. In other words, they extract water or moisture from the air adapted to flow thereover within the cabinet, the amount of moisture extracted depending to a large extent upon the temperature of the evaporator. If the temperature of the evaporator is above 32° F. as in room cooling apparatus, then the moisture collecting on the evaporator does not freeze but runs off or drains into some sort of receptacle located either within or without the cabinet. If the temperature of the evaporator is maintained below 32° F. as in refrigerators of the household type, then the moisture extracted from the air freezes on walls of the evaporator in the form of frost. Even in this latter case it is necessary to periodically dispose of the frost or ice since it acts as an insulator. Heretofore this has been done manually, but recently automatic devices, such as that shown in the King Patent 1,658,340 and the Raney Patents 1,877,967 and 1,867,711, have been suggested for performing this function automatically. This is done by periodically increasing the temperature of the cooling unit above the freezing point so that the frost melts from the cooling unit. The drip-water resulting from melting frost from walls of the cooling unit has been customarily collected in some sort of receptacle located within or without the cabinet. If this receptacle is not emptied at the proper time, it is likely to overflow and cause considerable trouble and dissatisfaction.

In the application of Richard S. Gaugler, Serial No. 672,916, filed May 26, 1933, there is disclosed an electrical means which will dispose of the drip-water from any cooling means automatically. In the application referred to, there is disclosed a plurality of spaced apart plate-like electrodes disposed in a drip catching receptacle, which electrodes are connected with an electrical power circuit, and upon being bridged by a body of drip-water accumulating in the receptacle electric energy flows from one electrode to the other through the water, thus heating the water, due to resistance to the flow of current therethrough, and causing evaporation thereof. While the de-

vice disclosed in the application referred to has been used and found to be somewhat satisfactory in its function to carry out the results desired, it nevertheless inherently has certain difficulties which I propose to overcome or eliminate. For example, the device disclosed in the application above referred to at best causes evaporation of the drip-water only very slowly and if adjusted or constructed to cause rapid evaporation of the water from the receptacle, sufficient current passes through the water to each electrode to cause a short circuit of such intensity that fuses in the electrical circuit are likely to be blown.

It is therefore an object of my invention to provide an improved electrical means which will dispose of the drip-water from a cooling element automatically and more rapidly than has heretofore been accomplished without requiring the user's attention.

It is a more specific object of my invention to utilize the small amount of electric current ordinarily flowing through water between two electrodes in a drip collecting receptacle of a refrigerating apparatus to complete another electrical circuit leading to an electrical heater, mounted in thermal association with but isolated from the body of drip-water in the receptacle, for energizing the heating element and causing the body of the water to be rapidly vaporized or evaporated from the receptacle.

It is a further object of my invention to provide an electrical water evaporating device whose effectiveness is initiated by the accumulation of a predetermined amount of water in a receptacle and which remains effective for a considerable length of time after the level of water is reduced far below the level thereof which initiates the effectiveness of the device to insure evaporation of a large body of water each time the device is rendered effective.

In carrying out the foregoing objects, it is a still further object to provide an improved electrical means that will be efficient in its function of rapidly disposing of drip-water from a cooling unit of a refrigerating apparatus and which will be compact and of low manufacturing cost.

Further objects and advantages of the present invention will be apparent from the following description, reference being had to the accompanying drawing, wherein a preferred form of the present invention is clearly shown.

In the drawing:

Fig. 1 is a front elevational view of a mechanical refrigerator having my invention embodied therein;

Fig. 2 is an enlarged fragmentary sectional view showing a drip-water evaporating means constructed in accordance with my invention and showing the electrical circuit diagrammatically connected therewith; and

Fig. 3 is a sectional view of the lead-in plug carrying the electrodes employed in my device.

Referring to the drawing, for the purpose of illustrating my invention, I have shown in Fig. 1 thereof a refrigerator cabinet 20 having a food compartment 21 and a machinery compartment 22. The food compartment 21 is surrounded and formed by insulated walls 23 and is cooled by means which includes an evaporator or cooling unit 24 and a refrigerant liquefying means or unit 25. The refrigerant liquefying unit 25 comprises a compressor 26 for compressing the refrigerant and for forwarding the compressed refrigerant to the condenser 27 where the refrigerant is liquefied and collected in a receiver 28. From the receiver 28 liquid refrigerant is forwarded under pressure, through a suitable conduit 29 under the control of a suitable automatic expansion valve 30, to the cooling unit 24. The liquid refrigerant within the cooling unit 24 evaporates because of the absorption of heat from the air within the food compartment 21 and is returned to the compressor 26 through the return conduit 31. The compressor 25 is driven by an electric motor 32 through suitable connections such as the pulley and belt means 33.

The operation of the electric motor 32 and the compressor 25 is under the control of an automatic switch 34 which may be of any suitable type such as that shown in the King Patent 1,658,340 or that shown in one of the Raney Patents 1,877,967 and 1,867,711. This automatic switch 34 is under the control of a thermostatic bulb 35 which may be mounted in contact with any desired portion of the cooling unit 24. The automatic switch 34 is connected into electrical supply conductors 37 to open and close the electric motor circuit at suitable intervals to properly control the temperature of the cooling unit 24.

The automatic switch 34 normally controls the temperature of the cooling unit so that its temperature is maintained below water freezing temperatures. This causes frost to collect on walls of the cooling unit and the automatic switch 34 is of the type to periodically cause the temperature of the cooling unit 24 to increase above water freezing temperature so that frost accumulated on the walls of the cooling unit will melt therefrom. Instead of this type of control, the switch may so control the cooling unit temperature, as is ordinary in room cooling apparatus, that it is maintained at all times above the freezing temperature.

The drip-water resulting from the melting of frost from walls of the cooling unit drips from the cooling unit or evaporator 24 and flows into a tray or into a trough or cutter 40 as herein disclosed as being formed in the bottom of the lining member of the food compartment and located directly beneath the evaporator 24. A tube 41 which passes through the bottom of the insulated wall of the food compartment into the machine compartment 22 is connected with the tray or with the lowermost portion of the trough or cutter 40. The lower end of tube 41 extends to a point spaced slightly from the bottom wall of a cup-shaped member 42 to form in cooperation with the drip-water a liquid trap or seal at the end of tube 41 to prevent vapor or air from

ascending into the food compartment. The cup member 42 is secured to the underside of the bottom wall of the food compartment by screws or bolts 43 and is provided with a plurality of openings 44 for permitting drip-water to overflow therefrom. Surrounding the cup member 42 is a small generally cylindrical receptacle or tank 45. Receptacle or tank 45 has a flange 46 abutting and secured to the bottom wall of the insulated food compartment by screws or bolts 47. A threaded opening 48 is provided in the lower portion of the side wall of tank 45 and is closed by a bakelite or porcelain plug 49 and a gasket 50. A plurality of openings 51 are provided around the upper part of tank 45 for a purpose to be hereinafter described. The insulating plug 49 has two electrodes 52 and 53 preferably molded therein in spaced apart relation. The electrodes 52 and 53 are sealed in the plug 49 and extend entirely therethrough so as to have the inner ends thereof exposed to the interior of the tank 45 and so as to have the outer ends thereof adapted to receive an electrical connection. Thermally associated with or secured to the bottom wall of tank 45, in any suitable manner, there is located an electrical heating unit 55 containing a resistance winding 56 suitably insulated and having a connection with each of the lead-in terminals 57 and 58. It is to be understood that the receptacle 45 may be, if desired, mounted exteriorly of the compartment 22 and cabinet 20.

A switch unit including a heater comprising an electrical resistance wire 61 spaced from and adapted to heat a bimetallic thermostatic element 62 is shown as mounted in any desired location within the machine compartment 22 of the cabinet. As shown in Fig. 2 of the drawing this switch unit is preferably carried by the blocks 63 and 64 secured to the underside of the bottom wall of the insulated food compartment. The resistance or heater wire 61 is spaced slightly from the thermostat 62 and has terminal connections 65 and 66. The terminal connection 65 of heater 61 is connected with and includes a terminal for the conduction of current through the bimetal thermostat 62. The thermostat 62 carries at its free or movable end a contact 67 adapted to engage a contact 68 carried by a terminal 69 mounted in the block 64. It is to be understood that the switch unit just described may be located in a box or the like enclosure and mounted wherever desired.

The electrical circuit connected in parallel with the power supply conductors 37 of switch 34 and motor 32 and leading to the electrode 52, heater 55, thermostat 62 and heater 61 will now be described. Referring to Fig. 2 of the drawing wherein this electrical circuit is illustrated diagrammatically, there is a wire 71 which is connected with one of the power supply conductors 37 (see Fig. 1) and which leads to the terminal 72 attached to the electrode 53. A branch wire 73 connects the terminal 58 of heater 55 and resistance wire 56 located therein with the wire 71. A wire 74, connected to the other of the power supply conductors 37 (see Fig. 1) of the circuit to the motor and switch, is attached to the terminal 65 leading to heater 61 and thermostat 62. The terminal 66 of the heater 61, for thermostat 62, is connected by a wire 75 to a terminal 76 attached to the electrode 52. A wire 77 connects the terminal 69 with the terminal 57 of the heater 55.

The electrode 53 is connected at its binding post terminal 72 by wire 71 with the source of

electrical supply at all times and the electrode 52 is likewise connected at its binding post terminal 76 with the source of electrical supply through wire 75, terminal 66, thermostat heater 51, terminal 65, and wire 74. This causes the electrodes to be charged with electrical energy at all times and maintains an electrical potential between them. However, since these electrodes are insulated from one another there is ordinarily no current flowing between them and no electric energy is used. In practicing my invention it will be understood that the heater wire 61 for the thermostat switch is preferably of greater resistance to flow of electric energy than the drip-water in receptacle 45 so that when the electrodes 52 and 53 are bridged by the water the amount of current passing through wire 61 is sufficient to cause heating of the wire for effecting the thermostat 62.

20 When moisture or water drips from the cooling element or evaporator 24 for any reason whatsoever, such as during the defrosting period automatically initiated as described by the switch 34, this moisture or drip-water is caught in the trough 25 or cutter 40 and is conducted by conduit or tube 41 into the sealing cup 42 from which it overflows through the openings 44 into the receptacle or tank 45. The drip-water collects in the lower portion of tank 45 and when a sufficient amount 30 has been collected, the level of the water rises so that it contacts both of the electrodes 52 and 53. The drip-water upon contacting both electrodes causes a small amount of electric energy to flow from one electrode to the other through 35 the water. The arrangement is such that the amount of current flowing through the water is sufficiently to cause heating of the resistance wire 61 but preferably no appreciable heating of the water bridging the electrodes 52 and 53. The 40 amount of electric energy or current capable of being conducted from one electrode to the other through the water being in accordance with this invention sufficient to cause the circuit connecting the electrodes with the source of electric supply to be closed. Closing of this circuit through 45 wires 71, 74, and 75 causes heater 61 of thermostat 62 to be energized, thus generating heat and radiating same against or upon the bimetal element 62. Heating of the bimetal element 62 causes its free or contact carrying end to move 50 away from the heater wire 61 and toward the terminal 69. The contact 67, carried on the free end of the thermostat element 62, engages the contact 68 of terminal 69, thus completing or 55 closing the electric circuit leading to the secondary heater 55. It will be understood from the disclosure and description thereof, that the circuit to the heater 55 just described is made through good metallic conducting elements entirely independent of the water connection between the electrodes 52 and 53 and the resistance wire 61. Therefore electric energy is readily conducted to the resistance element 56 of heater 55 without passing through or being impeded by 60 other resistance means or elements in the circuit. The unit 55 and its resistance element 56 may be of any suitable well-known construction and arrangement as to generate considerable heat rapidly and are associated with receptacle 45 in 65 such manner as to transfer this heat to water in the receptacle. Other provisions obviously within the realm of my invention can be made, such, for example, as a secondary electric circuit of low voltage, to insure that very little electrical energy 70 will pass through the water, when the water 75

bridges the electrodes 52 and 53, to prevent blowing of fuses in the circuit. Thus provision to insure that the thermostat heater 61 generates only a small amount of heat sufficient to cause operation or movement of the bimetal member 62 as compared to the amount of heat generated or produced by the heating resistance element 56 are obvious. Consequently, when the heater 55 is rendered effective, drip-water in receptacle 45 is rapidly heated, without directly contacting the 10 heating element, and is caused to vaporize. The vapor resulting from evaporation of water in receptacle 45 rises and flows outwardly of the receptacle through the openings 51 and is carried away by air, circulated by the refrigerating 15 mechanism, sweeping over or around the receptacle.

When the contacts 67 and 68 are closed, to conduct electric energy directly through good metallic conductors, to the secondary heater 55, the 20 circuit between the electrodes 52 and 53 through wires 71 and 75, terminal 66, heater wire 61, terminal 65, and wire 74, remains closed as long as there is sufficient water in the receptacle 45 to bridge or contact both electrodes. As soon as 25 sufficient water has been evaporated or vaporized from receptacle or tank 45 to cause the level of the drip-water to be lowered or to fall below electrode 52, the electrical circuit leading to heater wire 61, through the electrodes 52 and 53 from 30 wire 71 and wire 75, will be broken, thus deenergizing the heater 61. Therefore, resistance wire 61 ceases to generate heat and the bimetal thermostat 62 begins to cool and after a predetermined period of time, according to the arrangement and location of the thermostat, the bimetal member 62 will move back into its normal position adjacent the heater wire 61. This movement of bimetal thermostat 62 is thus delayed for a predetermined length of time, depending on 40 the time required to cool same, and the contacts 67 and 68 remain closed for a period of time after the circuit to the thermostat heater 61 has been broken by the lowering of the water level below electrode 52. The heater 55 is thereby caused to 45 continue heating of the receptacle 45 until the contacts 67 and 68 are separated by the cooling and consequent movement of the thermostat 62. The prolonged breaking of the circuit to the heater 55 as accomplished in the manner described is desirable for the reason that it insures that substantially all of the drip-water contained in tank or receptacle 45 will be evaporated therefrom. Ordinarily a considerable length of time will therefore elapse before the level of drip-water in the receptacle 45 attains a height sufficient to again energize the electrical vaporizing system and operations of the thermostat 62 are thus minimized. The lapse of time between operations of energizing my electrical vaporizing 60 system can be predetermined to suit the required installation by constructing the tank 45 so that the distance between the electrode 52 and the bottom of the tank or receptacle will hold the desired amount of water in accordance with the 65 prolonged cooling and consequently movement of thermostat 62.

It will be seen that I have provided an extremely effective evaporating means for removing the drip-water from cooling elements of refrigerating systems. I have provided an improved means, over that disclosed in the Gaugler application referred to, in that my improved evaporating means will insure positive removal of a large amount of water thus being efficiently ap- 75

licable to room cooling or the like installations wherein drip-water flows from the cooling element or evaporator almost continuously. My improved evaporating means eliminates the 5 troubles, enumerated at the beginning of this specification, which have heretofore been incidental to the operation of mechanically cooled refrigerators.

While the form of embodiment of the invention 10 as herein disclosed, constitutes a preferred form, it is to be understood that other forms might be adopted, all coming within the scope of the claims which follow.

What is claimed is as follows:

15 1. A refrigerating apparatus including a cabinet, means for cooling air adapted to flow there-over mounted in said cabinet, said cooling means having moisture dripping therefrom, means for collecting the drip-water from said cooling means, 20 an electrical heating element for causing evapora-tion and removal of drip-water from said collecting means, means responsive to a predeter-mined accumulation of drip-water in said collecting means for initiating effectiveness of said 25 heating element, and a portion of said last named means being constructed and arranged to cause the effectiveness of said heating element to be prolonged for a predetermined period of time after the drip-water in said collecting means has 30 been diminished beyond the predetermined accumulation thereof for rendering the initiating means effective.

2. A refrigerating apparatus including a cabinet, means for cooling air adapted to flow there-over mounted in said cabinet, said cooling means having moisture dripping therefrom, means for collecting the drip-water from said cooling means, an electrical heating element disposed exteriorly of and in intimate thermal association 35 with said collecting means for causing evapora-tion and removal of drip-water therefrom, and means responsive to a predetermined accumulation of drip-water in said collecting means for rendering said heating element effective.

45 3. A refrigerating apparatus including a cabinet, means for cooling air adapted to flow there-over mounted in said cabinet, said cooling means having moisture dripping therefrom, means for collecting the drip-water from said cooling means, 50 an electrical heating element disposed exteriorly of and in intimate thermal association with said collecting means for causing evaporation and re-moval of drip-water therefrom, means responsive to a predetermined accumulation of drip-water 55 in said collecting means for initiating effectiveness of said heating element, and a portion of said last named means being constructed and arranged to cause the effectiveness of said heating element to be prolonged for a predetermined period of time after the drip-water in said collecting means has been diminished beyond the predetermined accumulation thereof for rendering the initiating means effective.

4. A refrigerating apparatus including a cabinet, 65 means for cooling air adapted to flow there-over mounted in said cabinet, said cooling means having moisture dripping therefrom, means for collecting the drip-water from said cooling means, an electrical heating element for causing evapora-tion and removal of drip-water from said collecting means, a pair of spaced apart electrodes disposed within said collecting means and insulated from one another, an electric circuit 70 connected to a source of electric supply and to said electrodes, an electric circuit connected to a

source of electric supply and to said heating element, a switch disposed in the circuit leading to said heating element and normally being in open position, means in said circuit leading to said electrodes for closing said switch to render 5 said heating element effective, and said switch closing means being rendered effective in response to a predetermined accumulation of drip-water in said drip collecting means.

5. A refrigerating apparatus including a cabinet, 10 means for cooling air adapted to flow there-over mounted in said cabinet, said cooling means having moisture dripping therefrom, means for collecting the drip-water from said cooling means, an electrical heating element for caus- 15 ing evaporation and removal of drip-water from said collecting means, a pair of spaced apart electrodes disposed within said collecting means and insulated from one another, an electric circuit connected to a source of electric supply and to said electrodes, an electric circuit connected to a source of electric supply and to said heating element, a switch disposed in the circuit leading to said heating element and normally being in open position, means in said circuit leading to 20 said electrodes for closing said switch to render said heating element effective, said switch closing means being rendered effective in response to a predetermined accumulation of drip-water in said drip collecting means, and said switch being 25 constructed and arranged to cause the effectiveness of said heating element to be prolonged for a predetermined period of time after the drip-water in said collecting means has been diminished beyond the predetermined accumulation 30 thereof for rendering said switch closing means effective.

6. A refrigerating apparatus including a cabinet, 35 means for cooling air adapted to flow there-over mounted in said cabinet, said cooling means having moisture dripping therefrom, means for collecting the drip-water from said cooling means, an electrical heating element for causing evapora-tion and removal of drip-water from said collecting means, a pair of spaced apart electrodes 40 disposed within said collecting means and insulated from one another, an electric circuit connected to a source of electric supply and to said electrodes, an electric circuit connected to a source of electric supply and to said heating ele- 45 ment, a bi-metal thermostatic switch disposed in the circuit leading to said heating element and normally being in open position, an electrical resistance unit disposed in said circuit leading to said electrodes, said resistance unit being 50 located adjacent said bi-metal thermostatic switch and adapted to heat same to cause closing thereof for rendering said heating element effective, and said switch closing resistance unit being rendered effective in response to a predetermined 55 accumulation of drip-water in said drip collecting means.

7. A refrigerating apparatus comprising in combination, means for cooling air adapted to flow there-over, said cooling means being adapted 65 to collect moisture thereon and to have moisture dripping therefrom, means for catching the drip water from said cooling means, and heating means for causing evaporation of drip water from said catching means, said heating means being 70 disposed exteriorly of and in intimate thermal association with said catching means and being normally ineffective and rendered effective automatically in response to a predetermined accumulation of drip water in said catching means.

8. A refrigerating apparatus comprising in combination, means for cooling air adapted to flow thereover, said cooling means being adapted to collect moisture thereon and to have moisture dripping therefrom, means for catching the drip water from said cooling means, and heating means for causing evaporation of drip water from said catching means, said heating means being normally ineffective and rendered effective automatically in response to a predetermined accumulation of drip water in said catching means, and means for prolonging the effectiveness of said heating means for a period of time after the drip water in said catching means has been diminished beyond a predetermined accumulation thereof by said heating means.

9. A refrigerating apparatus comprising in combination, means for cooling air adapted to

flow thereover, said cooling means being adapted to collect moisture thereon and to have moisture dripping therefrom, means for catching the drip from said cooling means, and heating means for causing evaporation of drip water from said catching means, said heating means being disposed exteriorly of and in intimate thermal association with said catching means and being normally ineffective and rendered effective automatically in response to a predetermined accumulation of drip water in said catching means, and means for prolonging the effectiveness of said heating means for a period of time after the drip water in said catching means has been diminished beyond a predetermined accumulation thereof by said heating means.

JACOB SMILACK.
